UNITED STATES PATENT OFFICE.

WILLIAM VERT WEBSTER, OF OTTAWA, ONTARIO, CANADA.

DOORCHECK.

Application filed June 5, 1928. Serial No. 283,058.

The object of this invention is the provision of a check for swinging doors in which spring means influences the door to closed position and fluid means offers a 5 resistance to the spring means so that the door will be quietly closed.

A further object is the provision of a door check in which the operating parts thereof are adjustable so that the device 10 may be successfully employed upon different sizes and weights of doors, and also whereby the pressure required in opening the doors may be accurately determined as may the automatic swinging of the doors 15 to closed positions.

A still further object is the provision of a check for doors that shall be connected directly to the door and the employment of swingable arms between the check and the 20 door casing entirely dispensed with.

A still further object is the provision of a door check that comprises few simple parts, easily assembled and readily disassociated so that any broken or injured part 25 may be quickly replaced.

To the attainment of the above broadly stated objects and others which will present themselves as the nature of the invention is better understood, the improvement also 30 resides in certain other novel features of construction, combination and operative association of parts, satisfactory embodiments of which are illustrated by the accompanying drawings.

35 In the drawings:

Figure 1 is a horizontal sectional view approximately on the line 1—1 of Figure 2.

Figure 2 is a side elevation illustrating the application of the improvement, the 40 door being swung to partly open position.

Figure 3 is a sectional view approximately on the line 3—3 of Figure 4.

Figure 4 is a sectional view approximately on the line 4—4 of Figure 3.

45 Figure 5 is a perspective view illustrating a slight modification, only a portion of the door being shown.

Figure 6 is a sectional view approximately on the line 6—6 of Figure 5.

50 Figure 7 is a side elevation with parts in section to illustrate the manner in which the improvement is attached to the door, the latter being also in section.

In the drawings, the numeral 1 designates 55 a door which is hinged in a door frame or casing 2. On the outer face of the door

either adjacent to the top or bottom thereof, I secure a cylinder 3. The cylinder has both ends open, its bottom being closed by a flanged disc 4 which is screwed on the 60 cylinder and its top being closed by a similar disc 5. The bottom 4 is centrally formed on its inner face with an upstanding boss 6 that is provided with a square opening which passes through the bottom 65 4, and in this opening and fixed to the mentioned boss 6, by pins 4', there is a metal post 7. The post is of a cross sectionally square formation for the major portion of its length but the outer end thereof is cross 70 sectionally round and threaded, as at 8. The cylindrical casing 3 is integrally formed with ears or lugs 9, which extend laterally from one of the faces of the casing, and which have openings that receive therethrough the means that secure the cylinder 75 on the door.

The top 5 is centrally formed with an opening whose wall is surrounded by a depending flange that merges into an in-turned annular flange and thus provides a packing box within which there is received a packing 10. Received through the packing box there is the tubular drive member 11 of the improvement. The drive member 80 85 is really in the nature of an elongated nut, the same being provided with interior threads 12 and the said threads are arranged at a pitch of approximately 45°. The tubular drive member 11 has on its 90 outer end a cylindrical head 13 which is peripherally provided with teeth 14.

Before the drive member 11 is arranged in the cylindrical casing 3, I position in the said cylinder a disc in the nature of a 95 plunger 15. The plunger has its bore corresponding to the square cross sectional contour of the post 7 and the said plunger is provided at spaced intervals with openings 16 that are normally closed by pivoted flat 100 valves 17, the said valves being preferably provided each with an aperture 17'. The plunger 15 is integrally formed with a screw extension 18 whose threads coengage with the threads in the bore of the tubular drive 105 member 11. The post 7 is surrounded by a helical spring 19 which exerts a tension between the plunger 15, and an adjustable element on the post 7, which will hereinafter be described in detail. A cap nut 20 is 110 screwed in the packing box provided by the top 5 to compress the packing therein and

to likewise provide a guide for the tubular drive member 11.

The head 13 has its outer face provided with an annular depression forming a race-way for antifrictional balls 21, the second element 22 of the race-way held screwed in the threaded end 8 of the post and being in contact with the balls 21 by a nut 23 which is also screwed on the end 8 of the post. I cut an angular opening through the portion 10 of the door 1 in a line with the teeth 14 on the head 13 of the drive member 11, as indicated by the numeral 24 in Figures 1 and 2 of the drawings. Through this opening 15 there is passed a curved rack 25. Both ends of the rack have offset portions in the nature of ears, the inner ear being secured to the inner or jamb member 2 for the door 3 and the outer ear being secured to the outer 20 member of the door casing, as clearly disclosed by Figure 1 of the drawings.

Preferably I fill the cylindrical body 1 with a fluid, such as oil of a light grade. The nut 23 is not screwed too tightly 25 against the member 22 so that the free turning of the drive member 11 is not impaired. When the door is swung to open position the drive member will turn the screw on the plunger 15, forcing the same 30 downwardly against the pressure of the spring 19. The movement of the plunger will cause the flat valves 17 to automatically open so that fluid from the part of the chamber below the plunger will flow through the 35 openings 16 into the upper portion of the receptacle 3, and only slightly resist the downward movement of the plunger. When the door is released the compressed 40 spring 19 will expand, moving the plunger 15 in an opposite direction and to its initial position. The upward movement of the screw with the plunger will cause the drive member 11 to turn in an opposite direction to that just described. The fluid 45 in the upper part of the cylinder 3 will now act on the valves to close the same, so that the plunger will offer a resistance to the spring to prevent the violent closing and banging of the door against the jamb or 50 casing. The fluid, however, will find a restricted passage through the apertures 17 in the valves 17, so that too great resistance is not offered the spring. Thus the door 55 closes quietly, but the same is held closed with sufficient pressure to prevent the said door being accidentally opened.

In order to adjust the tension of the spring 19 so that the device may be successfully employed upon different size and 60 weights of doors and likewise regulate the rapidity at which the doors are closed, I provide the lower portion of the post 7 with an elongated slot or opening 7'. This end 65 of the post has a central threaded opening therethrough that communicates with the

slot or opening 7' and engaging the threads in this opening there is a headed screw 50. The screw contacts with a pin 51 that passes transversely through the slot or opening 7', the said pin being received in a depression 70 in the lower or outer face of a disc 52, and on this disc the lower convolution of the spring 19 rests. The head of the screw 50 is kerfed for the reception of a screw driver bit or the like and by adjusting the screw 75 the disc 52 will be moved longitudinally and thereby compress or permit of the expansion of the spring 19.

The above description refers particularly to the construction disclosed in Figures 1 to 4 of the drawings, but the constructions in the remaining figures are substantially similar except that the cylindrical casing is inverted and is arranged adjacent to the bottom of a door. Also in figures 5 to 7 of 85 the drawings the door is designed to open inwardly while with the construction first described the door can be opened either inwardly or outwardly. The cylindrical casing is indicated by the numeral 42 and the cross sectionally squared post by the numeral 26. The plunger 27 is provided with openings 27' and has on its lower face spring influenced flat valves 28, each having a restricted opening or aperture 28' there-through. Surrounding the post and exerting a pressure thereagainst there is a helical spring 29. The plunger 27, on its lower face, is formed with a screw 30 whose threads have the same angle pitch as those of the screw 18. The screw has a square bore for the post 26. The screw 30 coengages with threads in the bore of a tubular drive member 31. The tubular drive member passes through a packing box in the removable bottom of the casing, and has on its outer end a round head 32 whose periphery is cut at an angle and formed with teeth 33. Freely journaled in a central opening in the head 32 and held from longitudinal movement therein there is the reduced end 34 of an angle shaft 35. The angle shaft 35 has an outer reduced end 40. Journaled on this end 40 there is a beveled toothed wheel 36 that is in mesh 115 with the teeth 33 of the wheel or head 32. The toothed wheel 36 is fixed to the inner face of a grooved roller 37, which is also journaled on the end 40 of the angle shaft 35 and in the groove of the roller 36 there 120 is a compressible ring or tread 38. The numeral 39 designates washers for holding the roller and the toothed wheel on the shaft 35. These washers are held on the end 40 of the shaft by a cotter pin or the 125 like. The operation of this form of the improvement is similar to that previously described. The cylindrical casing is arranged on the door in a manner whereby the tread 38 for the roller 37 will frictionally 130

contact with the floor surface so that the turning of the roller will turn the head or wheel 32 of the drive member 31, causing the screw 30 to move the plunger 27 upwardly in the casing 42 when the door is opened and thereby compress the spring 29. The expansion of the spring will turn the screw 30 in an opposite direction and thereby causing the drive member 31 to also turn in a second or opposite direction so that the turning of the roller 37 is reversed and the door brought to closed position. The valves 28 are fluid influenced to closed position when the spring influences the door to its closed position, so that the openings in the plunger are practically closed. The resistance offered the spring causes the door to be closed in a gentle manner.

The tension of the spring 29 is regulated by means similar to that described in connection with the post 7 and the spring 19. The cap flange 41 for the casing 42 of the construction just described has a central hub 55 that receives therein and has secured thereto the upper end of the post 26. The post 26 is slotted longitudinally for a determined portion of its length to provide the same with a transverse opening 43. Threaded through the outer or upper end of the post there is a screw 43' having a head which is kerfed, the said screw bearing against a pin 44 which is passed through the post 26 and is seated in a flanged washer 45 against which the spring 29 contacts.

The cylindrical casing 42 is formed on its faces with a boss 46. This boss has a threaded opening therein. The numeral 47 designates a plate or ear member that has a headed screw 48 passing therethrough and entering the threaded opening in the boss 46. The head of the screw 48 is pocketed in plate 49 and after the plate or ear is thus attached to the casing, securing means 50 are passed through openings in the said plate 49 and enter the door, and thereby effectively secure the device on the door.

The simplicity of my construction and the advantages thereof will, it is thought, be understood and appreciated by those skilled in the art to which such invention relates, when the foregoing description has been carefully read in connection with the accompanying drawings. I do not wish to be restricted to the precise details herein set forth and, therefore, hold myself entitled to make such changes therefrom as fairly fall within the scope of what I claim.

Having described the invention, I claim:

1. A check for swinging doors, including a casing which is filled with fluid and which is designed to be secured on a door, a square post fixed in one end of the casing and extending through the opposite end, a plunger having a screw extension having a square bore which is guided on the post, said

plunger having openings therethrough, apertured flap valves normally closing the openings, a coil spring surrounding the post and urging the plunger in one direction, means for adjusting the tension of the spring, a 70 tubular drive member entering the casing and having a threaded bore engaged by the screw, and a toothed head on the outer end of the drive member and means engaging therewith for turning said drive member. 75

2. A check for swinging doors, including a casing which is filled with fluid and which is designed to be secured on a door, a square post fixed in one end of the casing and extending through the opposite end thereof, a 80 plunger having a screw extension having a square bore which is guided on the post, said plunger having openings therethrough, pivotally supported apertured flat valves on the plunger arranged one over each opening, a 85 coil spring surrounding the post and urging the plunger in one direction, means arranged exteriorly of the casing for adjusting the tension of the coil spring, a tubular drive member entering the casing and having a 90 threaded bore engaged by the screw, and a toothed head on the outer end of the drive member designed for engagement with an element for the rotation of said drive member. 95

3. A check for swinging doors, including a cylindrical casing which is filled with a fluid and which is designed to be removably secured on a door, removable flanged discs closing the ends of the casing, a square post fixed on one of the disks of the casing and extending through the opposite disk, a disc plunger having a screw extension provided with a square bore which is guided on the post, said plunger having openings therethrough, a pivotally supported apertured flat valve arranged over each opening, a coil spring surrounding the post and urging the plunger in one direction, a rest for one end of the spring, adjustable means guided 100 through one end of the post, contacting with the rest and operable to impart a longitudinal movement to the rest to regulate the tension of the spring, a tubular drive member entering one end of the casing having 105 a threaded bore which is engaged by the screw, one of said disks having an inwardly directed packing box through which the outer end of the drive member passes, a toothed head on the outer end of the drive member, anti-frictional bearings between the drive member and the post, and an element 110 designed for engagement with the toothed head of the drive member for turning the latter when the door is swung. 115

4. A check for swinging doors including a casing having a fluid therein and which casing is designed to be secured to a swinging door, a post arranged centrally in the casing, having one end fixed in the casing 120 125 130

and its second end extending through the casing, and said post, for the major portion of its length being square in cross section, an apertured plunger in the casing having 5 a screw extension that surrounds the post, swingable valves over the apertures in the plunger, a drive member having a stem provided with a threaded bore in which the screw is received, means on the drive member for turning the same when the door is 10 swung, a coil spring surrounding the post and having one end contacting with the

plunger, a disc surrounding the post and engaged by the second end of the spring, said post having an elongated opening there-through and having one of its ends threaded, 15 a headed screw member passing through the said end of the disc and engaging the threads thereof and entering the opening in the said post, and a pin seated in the disc, 20 arranged transversely through the opening in the post and contacted by the screw.

In testimony whereof I affix my signature.
WILLIAM VERT WEBSTER.
